UNITED STATES PATENT OFFICE.

EDMUND BANNING MARSHALL, OF ROME, GEORGIA.

HOLDER FOR DENTAL BITE-TAKERS.

SPECIFICATION forming part of Letters Patent No. 757,133, dated April 12, 1904.

Application filed January 19, 1904. Serial No. 189,699. (No model.)

To all whom it may concern:

Be it known that I, EDMUND BANNING MARSHALL, a citizen of the United States, residing at Rome, in the county of Floyd and State of Georgia, have invented a new and useful Holder for Dental Bite-Takers, of which the following is a specification.

This invention relates to holders or clamps for holding the trial-plates used by dentists to secure impressions of the teeth and gums of patients to serve as guides in the making and setting of artificial teeth.

The object of the invention is to provide a device of the character specified which will hold the trial-plate firmly in position, so as to enable the operator to secure a perfectly clear and distinct impression of the teeth and gum structure of the patient's mouth with the impressions of the upper and lower jaws so related as to show the relative positions normally occupied by the jaws.

To this end the invention consists in an improved form of trial-plate holder and clamping device by means of which the trial-plate may be quickly and securely clamped to the lower jaw of the patient and held positively in a fixed position, so that when the jaws are brought together to impress the teeth and gum structure thereof upon the trial-plate there will be no slipping of the trial-plate with consequent distortion of the impressions thereon.

In the preparation of plates for teeth and other dental work requiring impressions of the patient's mouth to be taken it is usual to obtain such impression upon a prepared block or "bite-taker" of wax or similar material, so as to get the impression of both jaws on the block. These impressions, however, do not always represent accurately the normal position of the jaws, and the plates made therefrom are apt to be more or less ill fitting, and consequently a source of discomfort to the wearer. This is due in the main to the well-known tendency in biting to bring the teeth together upon the bite-taker with a slight lateral movement in addition to the movement of approximation of the jaws. The lateral movement of the jaws is apt to distort the impressions and to shift the position of

the bite-taker in the patient's mouth if not firmly secured therein.

In overcoming the difficulties above outlined and securing clear and distinct impressions of the teeth and gum structure of patients I employ the novel plate-holder and clamp hereinafter fully described and claimed, and illustrated in a preferred form of embodiment in the accompanying drawings, forming part of this specification, it being understood that various changes in the form, proportions, and exact mode of arrangement of the elements exhibited may be made without departing from the spirit of the invention or sacrificing its advantages.

In the drawings, Figure 1 is a perspective view of the trial-plate holder and clamp with the trial-plate indicated in dotted lines upon the supporting member. Fig. 2 is a view in side elevation of the trial-plate holder and clamp applied, the lower jaw of the patient being diagrammatically indicated in proper relative position to the trial holder and clamp and the trial-plate itself being shown in solid lines over the patient's lower teeth.

Referring to the drawings, in which corresponding parts are designated by similar characters of reference throughout the several views, 1 designates a frame of wire bent to present a pair of slightly-curved branches 2, each composed of two substantially parallel portions connected at their outer ends, as shown, and conforming to the curve of the lower jaw of a human being, it being understood that the frame will be furnished in different sizes, if necessary, to conform to the oral cavities of different sizes. The frame 1 is preferably composed of a single wire, and the ends thereof are firmly secured in a shank 3, of metal or other material, having a hook 4 extending downward therefrom at the end adjacent to the frame 1. The frame 1 is embedded in the trial-plate which supports the impression - wax, which serves as the bite-taker, and may be of any ordinary or preferred construction, as that indicated diagrammatically in dotted lines at 5.

To coöperate with the frame 1 and its shank, I provide a larger frame 6, which is also con-

structed, preferably, of a single wire and presents two branches 7, which correspond generally to the curve of the lower-jaw bone, so that when the apparatus is placed in position, 5 as shown in Fig. 2, the frame 6 will press against the flesh covering the lower-jaw bone and the rami of the jaw will overlie the spaces between the outer and inner portions of the two branches of the frame. The ends of the 10 wire constituting the frame 6 are extended upward from the plane of the two branches 7 and thence carried forward to be firmly secured in a shank 8, which is adapted for engagement with the hook 4, carried by the 15 shank 3, and which has threaded in its outer end a screw 9, whose head 10 is disposed downward and whose point engages a socket formed in the under surface of the shank 3.

In using the trial-plate holder and clamp as

- 20 above described the trial-plate is coated upon its upper and lower surfaces with a layer of beeswax or other suitable material to serve as a bite-taker and is then introduced into the mouth of the patient in the usual way.
- 25 The frame 6, with the screw in the shank thereof retracted, is then brought into position beneath the patient's lower jaw, with the shank of the frame engaging the hook 4 on the shank of the plate-holding frame. The 30 screw 9 is then turned in the opening provided therefor in the shank of the frame 6 until the end of the screw engaging the socket in the under surface of the shank of the frame 1 separates the shanks of the two frames and 35 so forces the frames 1 and 6 into clamping engagement with the patient's lower jaw. The trial-plate having been thus firmly secured in position within the patient's mouth, the bite will be taken when the patient closes 40 his mouth, and the impressions of both upper and lower teeth will be clear and well defined, as all tendency of the bite-taker to slip in the mouth of the patient during the operation of taking the bite will be positively prevented by means of the plate-holder and clamp.

Having thus described the construction and use of my invention, what I claim as new, and desire to secure by Letters Patent, is—

- 50 1. A device of the character specified comprising a trial-plate-supporting frame adapted to enter a patient's mouth, a clamping-frame movably connected with the plate-holding frame and adapted to extend under the patient's chin, and means for positively forcing

said frames into clamping engagement with the patient's lower jaw.

2. A device of the character specified comprising a trial-plate-holding frame of wire bent to conform to the curve of the patient's 60 lower jaw, a clamping-frame of wire movably connected with the plate-holding frame and adapted to extend under the patient's lower jaw, and means for forcing said frames into clamping engagement with the patient's lower 65 jaw.

3. A device of the character specified comprising a trial-plate-holding frame presenting two diverging arms each consisting of substantially parallel portions of wire spaced 70 apart to present an opening somewhat wider than the row of teeth in a patient's lower jaw, and means for positively clamping said frame upon the lower jaw of a patient.

4. In a device of the character specified, a 75 trial-plate-supporting frame having a forwardly-projecting shank, a frame extending beneath the patient's chin and also having a forwardly-projecting shank, means for connecting said frames for relative pivotal movement, and means disposed between the shanks for forcing the shanks apart and thereby causing the frames to clamp the patient's lower 80 jaw.

5. In a device of the character specified, a 85 trial-plate-supporting member having a downwardly-disposed hook thereon, and a member extending beneath the chin and removably engaging said hook, and means between said members for forcing them into clamping engagement with a patient's lower jaw.

6. In a device of the character specified, a trial-plate-supporting member having a forwardly-projecting shank, a downwardly-disposed hook at the rear end of said shank, a 95 clamping member removably engaging said shank and extending beneath the plate-holding member, said clamping member having a forwardly-projecting shank, and a screw threaded in the shank of the clamping member and engaging the under surface of the shank of the plate-supporting member.

In testimony that I claim the foregoing as my own I have hereto affixed my signature in the presence of two witnesses.

EDMUND BANNING MARSHALL.
